AUTOMATIC OVEREDGING MACHINE

Frank R. Piper and James M. Gardner, Fairfax, Ala., assignors to West Point Manufacturing Company, West Point, Ga., a corporation of Alabama

Application May 15, 1950, Serial No. 161,932

3 Claims. (Cl. 112—214)

1

This invention relates to sewing mechanism, and particularly to mechanism for automatically and continuously applying overedging or overseaming to an elongated cloth length. It is a primary object of the invention to provide a machine adapted to apply overedging or other stitching to an elongated moving cloth length in a continuous and uniform manner.

A further object is to provide in sewing mechanism means for quickly and simultaneously stopping the stitching and feeding mechanism upon interruption of the stitching operation for any reason.

A further object of the invention is to provide in continuously and automatically operating sewing mechanism means for unreeling a cloth supply roll without affecting the uniformity or continuity of the sewing operation.

Another object is to provide automatic sewing mechanism particularly adapted for operation in battery.

Further objects of the invention will be in part obvious and in part pointed out hereinafter.

The invention and the novel features thereof may best be made clear from the following description and the accompanying drawings, in which:

Figure 1 is a side elevational view of an exemplary embodiment of the present invention, adapted for the application of overedging to an elongated cloth length;

Figure 2 is a plan view of the mechanism of Figure 1;

Figure 3 is an end elevational view of the mechanism, taken on the line 3—3 of Figure 1;

Figure 4 is an end elevational view of the device, looking toward the discharge end;

Figure 5 is a sectional elevational view, on an enlarged scale, taken on the line 5—5 of Figure 2;

Figure 6 is a sectional elevational view, somewhat enlarged, taken on the line 6—6 of Figure 1;

Figure 7 is a view taken on the line 7—7 of Figure 6, showing details of the feed roll control switch operating mechanism;

Figure 8 is an enlarged view taken on the line 8—8 of Figure 2, showing details of the outfeed control mechanism of the device;

Figure 9 is a sectional view taken on the line 9—9 of Figure 8, showing further details of the outfeed control mechanism, and

Figure 10 is a schematic diagram illustrating the electrical and pneumatic systems of the device.

Referring to the drawings, in Figures 1 and 2 is shown an exemplary embodiment of the in-

2

vention, mounted on a frame 11 supported by standards 12. Laterally spaced arms 13 extend outwardly from one end of the frame, supporting at their outer ends the bearings 14, which cradle a spindle 15 and the supply roll 16 of cloth 17 wound thereon. In the example shown, the supply roll may constitute a continuous, elongated length of cloth, such as toweling, having one split edge to be reinforced by overedging.

10 The cloth length 17 is withdrawn from supply roll 16 by a cooperating pair of feed rolls 18, provided preferably with suitably roughened surfaces, between which the cloth passes. The cloth is fed by the feed rolls into a trough 19, wherein it forms a freely depending loop 20, and then passes over guide roller 21 to the platform 22 of the device. Guide collars 23 are adjustably positioned on the guide roller to assure proper alignment of the cloth length transversely thereof.

15 The cloth length is drawn across the table or platform 22 by a pair of outfeed rolls 24, suitably mounted on the machine frame at the discharge end thereof. To tension the cloth length in its traverse over the platform, a friction bar 25 is employed thereover at the platform end opposite the outfeed rolls, the friction bar being retained in adjacency to the platform at one end by stud 26 and at the other end by wing nut 27, the ends of the friction bar being suitably slotted to retain these elements. Intermediate the friction bar and the outfeed rolls, and disposed at one side of platform 22 is a conventional sewing machine 28, adapted in this example to apply overedging to the split edge of the cloth length. Thread to the sewing machine is supplied from suitably mounted bobbins 29. The stitching mechanism is well known in the art and is not in itself a part of the present invention, so that it requires no detailed description.

20 As best shown in Figure 4, the shaft 30 of lower outfeed roll 24 is rotatably mounted in bearings 32 fixed to the machine frame. Adjacent its ends, shaft 30 supports the apertured ends 33 of guide members 34, which extend thereabove and retain the guide blocks 35 affixed to respective ends of shaft 36 of the upper outfeed roll. Guide members 34 also enclose springs 37, which act against the stops 38 and constantly urge the guide blocks downwardly, thereby urging the upper outfeed roll toward the lower. As best shown in Figure 5, guide members 34 are joined at their upper ends by a beam 39, which is braced to the machine frame by strap 40. One guide member has a plate 41 fixed thereto (Figure 1), which supports pivot 42 of the roll lifting lever 43. As

shown in Figure 4, one end of lever 43 is disposed immediately below shaft 36 of the upper outfeed roll, in lifting engagement therewith.

The outfeed rolls 24 and sewing machine 28 are driven at predetermined relative speeds by a common shaft 44, powered through clutch 45 by drive shaft 46, which may be connected to any suitable source of power, not shown. Shaft 44 drives the sewing machine by means of pulley 47 mounted thereon and belt 48, which is also engaged to a pulley 49 of suitable diameter mounted on the stub shaft 50, supported on platform 22 adjacent the sewing machine. From the pulley 52 mounted on stub shaft 50, a belt 53 is connected directly to the sewing machine pulley 54. In this manner, the sewing machine is driven by shaft 44 at relatively high speed.

By means of sprocket 55 and chain 56, rotation of shaft 44 is also transmitted to sprocket 57 of reduction gear box 58, and thence through sprockets 59 and 60 and chain 62 to the shaft 63. By means of sprocket 64 mounted adjacent one end of shaft 63, the rotation thereof is transmitted directly through chain 65 to sprocket 66 fixedly mounted on shaft 30 near one end of lower outfeed roll 24. In this manner, the lower outfeed roll is driven at all times at predetermined speed relative to that of the sewing machine, although at much slower rate. The surfaces of the outfeed rolls are preferably roughened, and the upper outfeed roll being constantly urged toward the lower, the upper outfeed roll is satisfactorily driven from the lower by frictional engagement. Obviously, the upper and lower outfeed rolls may be interengaged by suitable gearing or otherwise, if desired.

As an outstanding feature of the mechanism, means are provided to stop the sewing machine and outfeed rolls simultaneously in the event the sewing machine fails to satisfactorily apply the desired line of overedging. In the exemplary embodiment, a bracket 67 is affixed to the frame of the machine intermediate the sewing machine and outfeed rolls, disposed transversely in operative alignment with the edge of the cloth length being worked upon. As best shown in Figures 5 and 8, bracket 67 carries a pivot 68, upon which a contact arm 69 is pivotally mounted. At the lower end of the contact arm, a foot 70 is adjustably affixed thereto, as by the bolt 72 extending through the foot and arcuate slots 73 of the contact arm. At its upper end, the contact arm supports electrical contact 74, mounted at the end of bolt 75, which is adjustably secured to the contact arm by means of nuts 76. By means of plate 77 supported on the frame, electrical contact 78 is similarly disposed, in adjacency to contact 74. The contacts 74 and 78 constitute a switch connected by conductor 79 and 80 in series with a solenoid operated three-way air valve 82.

The air valve 82 is conveniently mounted on one of the standards of the machine frame, as best shown in Figure 5, and pressure air is conducted thereto from a suitable source 81 (Figure 10) through tube 83. A flexible tube 84 leads from the air valve to single acting pneumatic cylinder 85, pivotally or otherwise suitably mounted at its lower end onto the machine frame. Cylinder 85 is provided with an elongated piston rod 86, extending therefrom through a suitable opening provided therefor in the strap 40, by which the outer end of the rod is retained and guided. A stop 87 limits outward movement of the piston rod. Midway of its length, the piston rod carries a pair of retaining collars 88, which serve to re-

tain helical springs 89, between which is disposed the apertured end portion 90 of clutch arm 92, extending from clutch 45 in the common drive for the sewing machine and outfeed rolls. The clutch 45, it will be understood, is of conventional type, operable into and out of engagement by swinging movement of the radially extending arm 92 associated therewith.

In order for the outfeed rolls 24 and friction bar 25 to function effectively to maintain constant tension in the cloth length therebetween, it is essential that the cloth be supplied to the friction bar in substantially untensioned state. The power required to unreel a heavy cloth roll is both considerable and variable, because of inertia and other factors, and in the present invention is supplied through feed rolls 18, effective to maintain between the feed rolls and friction bar 25 the free loop 28. To maintain the free loop, the drive of the feed rolls is controlled thereby, shortening of the loop being effective to start the feed rolls and lengthening of the loop operating to stop the feed rolls.

As shown, lower feed roll 18 is driven by motor 93, the motor shaft 94 being engaged in driving relationship by sprocket 95 and chain 96 to the sprocket 97, affixed to an end of the lower feed roll shaft 98. The lower feed roll is freely rotatable relative to shaft 98, but may be engaged thereto by means of the clutch indicated generally at 99 (Figure 3), comprising a driving member 100 engaged to shaft 98 and a driven member 102 affixed to the lower feed roll. The clutch members 100 and 102 may be leather faced or similarly conventionally constructed. As in the case of the outfeed rolls, the feed rolls may have suitably roughened surfaces, and the upper feed roll may be resiliently urged toward the lower, whereby the upper feed roll is frictionally driven by the lower.

To the end of the lower feed roll opposite clutch 99 is rotatably affixed a collar 103, pivotally engaged to yoke portion 104 of lever 105, which is pivotally mounted on the frame by pin 106. Collar 103, it will be understood, is connected to member 102 of the clutch 99 so that axial displacement of the collar results in corresponding axial displacement of member 102 into and out of engagement with the driving clutch member 100.

Means are provided below pivot pin 106 of the lever to actuate the lever and thereby the collar 103. As best shown in Figure 3, a single acting pneumatic cylinder 107 is suitably secured to the frame, its piston rod 108 being pivotally engaged to lever 105, whereby extension thereof will effect movement of collar 103 in the opposite direction and consequent engagement of clutch 99. Secured to the lower end of lever 105 and to some stationary portion of the mechanism, such as the body of cylinder 107, is provided a tension spring 109, which tends to maintain the piston rod of the pneumatic cylinder in retracted position, and the clutch 99 in disengagement. Pressure air is conducted to the pneumatic cylinder from a suitable source through tube 110 to a conventional solenoid operated three-way air valve 112, and thence through the tube 113 to the cylinder.

Over trough 19 and within the loop 20 formed by the cloth length is mounted a switch 114, connected in series by conductors 115 and 116 with the solenoid of valve 112. As best shown in Figures 1, 6 and 10, an annular cam 117 provided with a surface indentation 118 is rotatably

mounted in operative relationship with switch arm 119 of the switch 114. At its outer end, switch arm 119 carries the cam following roller 120. From cam 117 an elongated arm 121 depends, formed at its lower end into a cross bar 122, disposed parallel to the plane of the cloth length and of a length corresponding substantially to the width of the cloth. Arm 121 and cross bar 122 are preferably constructed of light weight materials, for reasons presently apparent.

The operation of the mechanism will now be described in detail. A roll 16 of cloth 17 being suitably placed upon the bearings 14, the cloth end may be threaded through feed rolls 18, thence downwardly into trough 19 below cross bar 122 of control arm 121, and thence upwardly over guide roller 21 and across the platform 22 of the device. After placement of the cloth thereunder, the friction bar 25 may be positioned and suitably anchored, and adjusted to frictionally engage the cloth length to the desired extent and thereby govern the tension in the length between the friction bar and the outfeed rollers. The tensioning effect of the friction bar may be adjusted by means of wing nut 21, by employing bars of different weights, or by similar expedient.

The split edge of the cloth length, of course, will be on the side corresponding to the position of sewing machine 28. The split edge is threaded therethrough and the cloth length then placed between the outfeed rolls 24. To facilitate this end, the outwardly extending end of lever 43 may be depressed downwardly, and the upper outfeed roll 24 lifted against the pressure of springs 31.

The foot 70 of contact arm 69 is so adjusted that when resting upon the unstitched thickness of the cloth length, the electrical contacts 74 and 78 will abut each other. As the line of overedging 123 is applied by the sewing machine, the foot 70 will ride thereon (see Figures 8 and 9), and the extra thickness thereof will raise the foot and cause the contact arm to be pivoted about pivot 68, whereby contact 74 will be displaced out of engagement with the contact 78.

Power being supplied through drive shaft 46, clutch 45 and shaft 44, the outfeed rolls and sewing machine will be driven at predetermined constant relative speeds, whereby the line of overedging applied by the sewing machine will be at all times uniform. In the event of breakage of the thread from one of the bobbins 29, or other malfunctioning resulting in failure of the sewing machine to apply the line of stitching 123, substantially immediately after such failure the foot 70 will drop over the end of the line of stitching and the contact arm 69 will rotate contact 74 against contact 78, whereby a circuit will be completed therethrough and through the solenoid of air valve 82, whereupon the air valve will be opened and piston rod 86 of pneumatic cylinder 85 caused to extend outwardly. Through the medium of retaining collars 88 and springs 89, the outward movement of the piston rod will cause corresponding rotation of the clutch arm 92, which is effective, it will be understood, to disengage clutch 45, whereupon the outfeed rolls and the sewing machine simultaneously come to a stop due to the friction of these elements and the drive system therefor.

In such event, the outfeed roll lifting lever 43 serves to facilitate withdrawal of the cloth length to the point at which stitching failure occurred, and the stitching failure may be corrected by replacement of the thread or similar required.

adjustment, and the operation of the sewing machine and outfeed rolls then restarted, as by rotating the contact arm 69 to lift foot 70. Breaking of the circuit through contacts 74 and 78 de-energizes the solenoid of valve 82, permitting the piston rod 86 to return to retracted position, whereby the clutch arm 92 is rotated in a manner causing engagement of clutch 45.

As previously indicated, the cloth length intermediate the outfeed rolls and the friction bar is at all times uniformly tensioned, thereby facilitating and improving the stitching operation. This, of course, would be impossible if cloth was drawn to the friction bar directly from a heavy cloth roll. In the present invention, however, cloth is supplied to the friction bar through a free loop, by the feed rolls 18. The shaft 98 of the lower feed roll is driven as previously set forth by the motor 93. The action of clutch 99, however, by which the feed roll is engaged to shaft 98, is controlled by pneumatic cylinder 107, through its piston rod 108, lever 105 and the collar 103. Spring 109 functions to maintain lever 105 and collar 103 in normal position, corresponding to disengagement of clutch 99.

In the event the free loop 20 is shortened, as by starting of outfeed rolls 24, the loop engages cross bar 122, of arm 121, thereby rotating the arm and cross bar from their normal dependent position and rotating cam 117 so that the roller 120 of switch arm 119 is lifted out of the cam indentation 118 and onto the outer periphery of the cam. This movement of the switch arm closes switch 114, whereby a circuit is completed therethrough, and through the solenoid of valve 112, which thereupon opens and permits pressure air from reservoir 81 to actuate cylinder 107 and displace its piston rod 108 outwardly. The outward movement of the piston rod displaces lever 105, and causes corresponding movement of collar 103 in the opposite direction, whereby engagement of clutch 99 is effected. Engagement of the clutch causes rotation of the feed rolls with shaft 98, which rotation feeds the cloth length until the loop 20 is lengthened sufficiently to permit arm 121 to fall to its normal downward position, as indicated by dotted lines in Figure 1, at which point roller 120 of switch arm 119 falls into the cam indentation 118, and switch 114 is permitted to open, the spring 109 being effective in such case to return piston rod 108 and lever 105 to normal position corresponding to disengagement of clutch 99. Obviously, in the event of stoppage of the outfeed rolls and sewing machine, the free loop 20 will immediately build up sufficiently to permit opening of switch 114, whereby the feed rolls will be similarly stopped.

The drive of feed rolls 18 is designed so that the rate of feed of the feed rolls exceeds that of outfeed rolls 24, so that during steady operation of the outfeed rolls, the feed rolls operate only intermittently to maintain within trough 19 a free loop adequate at all times to furnish a substantially untensioned length of cloth to the friction bar 25. The feed roll drive is adequate to overcome the inertia of and satisfactorily unwind cloth roll 16, and functions in the mechanism to maintain the untensioned free loop 20 whereby the outfeed rolls 24 may operate in conjunction with friction bar 25 to maintain a cloth length therebetween of even tension at all times during operation. The arm 121 and cross bar 122 are preferably of light construction, so that displacement thereof causes

substantially no tension in the cloth length approaching the friction bar.

The electrical and pneumatic systems of the machine are diagrammatically illustrated in Figure 10 of the drawings, wherefrom the operation thereof will be entirely clear to those skilled in the art.

Due to the clutch mechanisms incorporated in the drive systems, and the controls therefor, the machine is particularly adapted for use in battery, it being apparent that drive shafts 46 and 94 may be extended and employed to drive two or more machines of the same type. In this event, stoppage of the outfeed of one machine by reason of failure of the stitching operation thereof will in no way affect the continued operation of the other machines in the battery, and, similarly, the intermittent operation of the feed rolls of each machine will be independent of and not affect the corresponding operation of the feed rolls of the other machines in the battery.

While particularly adapted for applying over-edging or other stitching to an edge of an elongated cloth length, it will be evident that the mechanism is not limited in utility to such specific purpose, but may be readily altered by mechanical adaptation to apply a line of stitching to the cloth length at points intermediate its edges.

It will thus be seen that there has been provided by this invention a structure in which the various objects hereinbefore set forth, together with many practical advantages, are successfully achieved. As various possible embodiments may be made of the mechanical features of the above invention, all without departing from the scope thereof, it is to be understood that all matter hereinbefore set forth or shown in the accompanying drawings is to be interpreted as illustrative, and not in a limiting sense.

We claim:

1. Sewing mechanism comprising a pair of parallel, opposed, cooperating outfeed rolls adapted to displace an elongated cloth length between the bite thereof, frictional means adapted to tension the cloth length approaching said outfeed rolls and riding transversely on said cloth length uniformly across its width, a sewing machine disposed intermediate said outfeed rolls and tensioning means and adapted to apply stitching to the cloth length, means for driving said outfeed rolls and sewing machine at constant relative speeds, feeler means adapted to ride the line of stitching intermediate said sew-

ing machine and outfeed rolls, and means actuated by said feeler means to deactivate said driving means in the absence of stitching.

2. Sewing mechanism comprising a pair of parallel, opposed, cooperating outfeed rolls adapted to displace an elongated cloth length between the bite thereof, a platform disposed and adapted to support the cloth length approaching said outfeed rolls, frictional means associated with said platform adapted to tension the cloth length approaching said outfeed rolls and riding transversely on said cloth length uniformly across its width, a sewing machine disposed laterally of said platform intermediate said outfeed rolls and tensioning means and adapted to apply stitching to the cloth length, means for driving said outfeed rolls and sewing machine at constant relative speeds, a clutch in said driving means, a feeler adapted to ride the line of stitching intermediate said sewing machine and outfeed rolls, a switch operated by said feeler, and means controlled by said switch operative to actuate said clutch.

3. Sewing mechanism comprising a pair of parallel, opposed, cooperating outfeed rolls adapted to displace an elongated cloth length between the bite thereof, frictional means adapted to tension the cloth length approaching said outfeed rolls and riding transversely on said cloth length uniformly across its width, a sewing machine disposed intermediate said outfeed rolls and tensioning means and adapted to apply stitching to cloth length, means for driving said outfeed rolls and sewing machine at constant relative speeds, means adapted to ride the line of stitching intermediate said sewing machine and outfeed rolls and deactivate said driving means in the absence of stitching, and means for continuously and automatically supplying untensioned cloth to said tensioning means.
